UNITED STATES PATENT OFFICE.

HARRY M. ROSENBLATT, OF PHILADELPHIA, PENNSYLVANIA.

TRAVELING-CASE.

SPECIFICATION forming part of Letters Patent No. 624,981, dated May 16, 1899.

Application filed December 30, 1898. Serial No. 700,690. (No model.)

To all whom it may concern:

Be it known that I, HARRY M. ROSENBLATT, a citizen of the United States, residing at Philadelphia, county of Philadelphia, and State of Pennsylvania, have invented a new and useful Improvement in Traveling-Cases, of which the following is a full, clear, and exact description, reference being had to the accompanying drawings, which form a part 5 of this specification.

My invention relates to a traveling-case, and particularly to that style of case which is provided with a compartment-box for the reception of such articles as it may be desired 10 to keep separate from those in the body of the case. The objection to cases having rigid-wall compartments is that the user frequently makes no use of the compartment or only partly fills it, so that the compartment occupies needless space and is of doubtful utility. 15 The objection to cases having flexible-wall compartments is that when wholly or partly filled they bulge out more or less unevenly and destroy the otherwise even and regular 20 contour of the body of the case.

The object of my invention is to provide a compartment which will extend along one of the inner walls of the case and which while constructed so as to be flexible in the sense 25 of being compressible and extensible is so constructed as to be capable of compression or extension without affecting the parallelism of the outer or front wall of the compartment-box with the wall of the case to which 30 the box is secured, thus preserving the even outline of the main body of the case, while providing for the uniform and (in a sense) 35 automatic compression of the box as the main body of the case is filled.

40 A further object of the invention is to provide means whereby this expansion or contraction may be effected without disengaging the fastenings by means of which the lid of the compartment-box is secured to the front 45 wall thereof.

Another object of the invention is to combine with the said compartment-box a jewel-case or collar and cuff button receptacle and to so locate it that while located substantially

within the compartment-box and occupying 50 no substantial space within the main body of the case it will always be accessible without the necessity of unfastening the lid of the compartment-box.

The invention consists, generally speaking, 55 of a compartment-box having extensible and compressible ends, bottom, and lid, this capacity being secured, preferably, by corrugating, creasing, or plaiting said ends, bottom, or lid centrally and longitudinally, the 60 lid having an extension which is provided with fixed fasteners and is adapted to fold down upon the front wall of the compartment and engage supplementary fixed fasteners 65 thereon.

The invention also consists in combining 70 with the compartment-box a jewel-case which is built into the front wall of the compartment-box and extends into the compartment and which is provided with a lid exterior to 75 the compartment, so that access may be had to the jewel-case without disengaging the lid of the compartment-box. The particular use for which the compartment is designed is to provide a receptacle for collars and cuffs. 75

In the drawings, Figure 1 is a perspective view of the case and compartment-box. Fig. 2 is a transverse section through the compartment-box and the case. Fig. 3 is a perspective view, partly in section, of the two 80 parts of the compartment-box folded, but before they are secured together and applied to the case. Fig. 4 is a plan view of the blanks of the two parts, the dotted lines showing the 85 lines of folding.

A is the case, B the rear wall thereof, and CD the two blanks of which the compartment-box is composed. The blank C is first cut out in the shape shown in Fig. 4 and then folded on the dotted lines to form the front 90 wall 8, the bottom 9 10, and the ends 6 7 6 7. The extra folds 5 5 of the end pieces are bent, as shown in Fig. 3, while the extra fold 11 of the bottom is bent, as shown in the same figure, so as to lie behind the folds 5 5. The 95 blank D is first cut out in the shape shown in Fig. 4 and then folded on the dotted lines to form the top, lid, or cover 2 3, the rear ex-

tension 1, (which is bent down, as shown in Fig. 3, so as to lie behind the folds 5 5,) and the depending extension 4. The overlapping parts of the blanks are then secured together by glue or otherwise and the folds 5 5, 1, and 11 secured to the wall B of the case. After the compartment-box is thus fastened to the case a layer of material G, preferably paste-board, covered with canvas g', is secured to the folds 5 5, 1, and 11 and also to the wall B, the compartment-box as a whole being thereby firmly secured to the case. The depending extension 4 and the front wall 8 are provided with fastening devices adapted for mutual engagement, whereby the compartment-box may be closed. These fastening devices preferably consist of orifices in the depending extension 4 and ordinary spring-catches E on the front wall.

20 Midway between the fastening devices and beneath them a jewel-case or collar and cuff-button receptacle F is built into the front wall of the box, as best shown in Fig. 2, the main body of the same extending within the compartment, while the lid f of the same (which may be an ordinary spring hinged lid locked by any suitable catch) is exterior to the box, enabling the user to have access to the case without disengaging the fastening devices of

30 the box.
Inasmuch as the bottom, ends, and top of the compartment-box are longitudinally creased it will be readily seen that the compartment-box as a whole may be compressed without disengaging the connections or affecting the substantial parallelism of the front wall 8 of the box with the wall B of the case. Collars and cuffs may be placed in the box flat, and as the main body of the case is filled the wall

40 8 will be forced in toward the wall B until the wall 8 engages the contained collars and cuffs, preventing further compression.

Having now fully described my invention, what I claim, and desire to protect by Letters

45 Patent, is—

1. In a traveling-case, the combination therewith of an extensible and compressible compartment-box extending along one of the inner walls of the case, the two ends thereof 50 and the bottom thereof being longitudinally creased, and provided with a folding lid also longitudinally creased, the lid having a depending extension, and a fixed fastening device, one part of which is on the front wall of the box and the other part on the depending extension and adapted to engage each other, whereby the compartment-box may be extended or compressed without disengagement or readjustment of said fastening device, 60 while maintaining the substantial parallelism of the front wall of the box and the said wall of the case.

2. In a traveling-case, the combination therewith of an extensible and compressible 65 compartment-box extending along one of the

inner walls of the case and formed of two blanks; one blank consisting of the piece 8, forming the front wall of the box having a side wing and two end wings longitudinally creased to form a plurality of folds, the end folds of each wing being bent inwardly into substantial parallelism with the front wall 8, the end fold of the side wing engaging the end folds of the end wings, the remaining folds of the end wings forming the ends of the box, and the remaining folds of the side wing forming the bottom of the box; the other blank being creased to form a plurality of folds, the fold at one end being bent into substantial parallelism with the front wall of the box and engaging the outer folds of the end wings, the fold at the opposite end being bent down over the front wall of the box, and the intermediate folds forming the top of the box.

3. In a traveling-case, the combination therewith of an extensible and compressible compartment-box extending along one of the inner walls of the case and formed of two blanks; one blank consisting of the piece 8, forming the front wall of the box having a side wing and two end wings longitudinally creased to form a plurality of folds, the end folds of each wing being bent inwardly into substantial parallelism with the front wall 8, the end fold of the side wing engaging the end folds of the end wings, the remaining folds of the end wings forming the ends of the box, and the remaining folds of the side wing forming the bottom of the box; the other blank being creased to form a plurality of folds, the fold at one end being bent into substantial parallelism with the front wall of the box and engaging the outer folds of the end wings, the fold at the opposite end being bent down over the front wall of the box, and the intermediate folds forming the top of the box, 95

4. In a traveling-case, the combination therewith of an extensible and compressible compartment-box extending along one of the inner walls of the case, and having a flat front wall, a bottom longitudinally creased to form 115 at least three folds, two ends similarly creased, the end folds of the bottom engaging the end folds of the ends, said end folds being bent inwardly, and a top longitudinally creased so as to be expansible and compressible similarly 120 to the bottom and ends, and having its inner end fold bent inwardly into engagement with the end folds of the ends.

5. In a traveling-case, the combination therewith of an extensible and compressible 125 compartment-box extending along one of the inner walls of the case, and having a flat front wall, a bottom longitudinally creased to form at least three folds, two ends similarly creased, the end folds of the bottom engaging the end 130

5 folds of the ends, said end folds being bent inwardly, and a top longitudinally creased so as to be expansible and compressible similarly to the bottom and ends, and having its inner end fold bent inwardly into engagement with the end folds of the ends, and a layer of material secured to the end folds of the bottom, ends and top and the said wall of the box.

In testimony of which invention I have hereunto set my hand, at Philadelphia, on 10 this 24th day of December, 1898.

HARRY M. ROSENBLATT.
